UNITED STATES PATENT OFFICE

ARTHUR G. GLASGOW, OF LONDON, ENGLAND, ASSIGNOR TO THE U. G. I. CONTRACTING COMPANY, OF PHILADELPHIA, PENNSYLVANIA, A CORPORATION OF DELAWARE

MECHANICALLY-CLINKERED GAS GENERATOR

Application filed March 29, 1926, Serial No. 98,142, and in Great Britain May 6, 1925.

This invention has reference to generators for the production of water-gas, producer gas, or the like provided with rotary grate structures designed to effect mechanical 5 clinkering of the fuel-beds and more especially to such generators as have water-sealed grate structures.

According to the invention the rotary grate structure of a mechanically clinkered generator is supported by annular surfaces resting one upon another and forming a gas-tight sliding joint adapted to prevent escape or short circuiting of air, steam or gas. These surfaces may be the lower and upper surfaces 15 of a ring formed on or attached to the underside of the grate structure and a fixed ring respectively, one of which may be formed with a flange to serve as a guide to prevent lateral displacement of the grate structure.

While more especially applicable to water sealed gas generators, this invention may be advantageously applied to completely enclosed mechanically clinkered generators for better support and guidance of the rotating 25 portion and to prevent the short-circuiting of the grate proper by air and steam, and also down-run gas in the case of water-gas generators, which short circuiting not only carries dust and ashes to the driving gear and journals, but, in the case of water gas generators, 30 encourages undesirable combustion near the bottom which leads to damage to the lower parts of the generator.

In the accompanying drawings:

Figure 1 shows in vertical section the lower part of a self-clinkering water-gas generator of the kind in which the rotary grate, supported by annular surfaces according to the present invention, is formed with an outer 35 water seal through which the clinker is continuously discharged to the atmosphere. Figure 2 is a similar view illustrating the present invention applied to a completely enclosed self-clinkering generator of the kind 40 in which there is a dry seal.

Referring to Figure 1, *a* is an annular water jacket surrounding the lower portion of the fuel bed and the inner wall of which forms part of the generator wall surrounding 45 a gas generating chamber *b*. *h* is a rotary

bottom or base plate carrying a cylinder or drum *g*¹ set eccentrically and having a conical cover or upper portion *g* formed with air passages. The bottom *h* also carries an annular wall *h*¹ forming between it and the cylinder 55 or drum *g*¹ a water seal trough into which depends from the jacket *a* an apron *l*. The grate structure comprising the parts, *h*, *h*¹, *g*, and *g*¹, is rotated by an electric motor 4 geared to the structure, the discharge of ash and clinker 60 through the water seal being thus effected by means of an inclined plough *t* up which the clinker and ash is propelled by shallow ribs *h*² on the wall *h*¹.

According to the present invention the rotating grate structure is constructed to form, in addition to the outer water seal around the lower edge of the generator wall, a gas-tight sliding joint around the conduit *k*; preferably the underside of the rotary base 65 plate *h* is formed or provided with a ring 10 and a ring 11 is carried by a fixed supporting wall or foundation 12, the lower and upper surfaces of the rings 10 and 11 resting one on the other and forming the gas-tight sliding 70 joint and also serving as the bearing surfaces which evenly support the entire grate structure and superimposed fuel-bed. Conduit *k* serves to admit air to the gas generating 75 chamber *b* and also has steam inlet means *s* thereon. One of the rings 10 or 11 may be formed with a flange which overlaps internally or externally the other and serves as a 80 guide to prevent lateral displacement of the rotating grate structure; in the drawings the lower ring 11 is shown with an external flange 85 11^a. Other guiding means may be employed. Suitable provision is made for supplying a lubricant to the bearing surfaces which facilitates them sliding one over the other and tends to ensure tightness of the joint; usually the fixed ring 11 will be flanged externally as referred to and of channel section so as to retain the lubricant. The rings 10 and 11 may be of different metals and either or 90 both may be provided with renewable wearing surfaces.

Between the fixed ring 11 and the conduit *k* a floor 14 is provided to which the said conduit is connected. The conduit *k* 100

may be extended upwardly through this floor above the level of the sliding joint. The annular chamber thus formed may be charged with water or other liquid or lubricant to above the level of the sliding joint. When liquid is employed, a supply pipe 15 and an overflow pipe 16 may be provided. By thus charging the annular chamber, gas and steam are kept from contact with the joint and from possible leakage to the atmosphere, the accumulation of a dangerous explosive mixture within this almost closed chamber is obviated, dust is prevented from reaching the joint, and the lubrication of the joint is ensured or improved. The mouth of the conduit h is overlapped by an annular plate 17 attached to the bottom h around its opening so that ashes falling through the grate will be directed into said conduit.

20 The arrangement comprising a sliding annular metal joint not only provides a positive inner seal requiring but little space vertically, but also takes the heavy weight and side thrust.

25 In Figure 2, which represents a self-clinkering generator having a dry seal the improvements hereinbefore described with reference to Figure 1 of the accompanying drawings are embodied and the same reference letters and numerals are applied to similar parts.

It will be obvious to those skilled in the art to which the invention relates that modifications may be made in details of construction and arrangement and in matters of mere form 35 without departing from the spirit of the invention which is not limited to such matters or otherwise than the prior art and the appended claims may require.

I claim:

40 1. In a mechanically clinkered gas generator, a gas generating chamber having pipe connections for admitting air and steam thereto, a rotating grate structure, and annular surfaces supporting said rotary grate structure and resting in contact one upon another, the lower and upper surfaces consisting of a ring provided on the grate structure and a fixed ring respectively and one of said rings provided with a flange which over- 50 laps the other ring.

2. In a mechanically clinkered gas generator, a gas generating chamber having pipe connections for admitting air and steam thereto, a rotating grate structure, and annular surfaces supporting said rotary grate structure and resting in contact one upon another, the lower and upper surfaces consisting of a ring provided on the grate structure and a fixed ring respectively, and the lower 55 fixed ring being of a channel section adapted to retain lubricant.

3. In a mechanically clinkered gas generator, a gas generating chamber having pipe connections for admitting air and steam thereto, a supporting joint consisting of con-

centric annular surfaces resting in contact one upon another, a floor, a grate structure, and an air blast conduit extending above the floor and providing with the joint and the grate structure and the floor a compartment adapted to receive liquid to flood the joint.

4. In a mechanically clinkered gas generator, a gas generating chamber having pipe connections for admitting air and steam thereto, a rotating grate structure comprising an outer water seal, a fixed ring, and an inner gas-tight sliding contact joint formed by and between an annular ring provided on the grate structure and said fixed ring, said joint preventing escape of gas intended for passage through the generator and supporting said rotary grate structure.

5. In a mechanically clinkered gas generator, a gas generating chamber having pipe connections for admitting air and steam thereto, a rotating grate structure, a stationary conduit for the passage of air into said generating chamber, a sliding joint supporting said rotating grate structure and forming a gas-tight joint for preventing the escape of gas from beneath said rotating grate structure, and a water seal sealing the joint between said conduit and said rotating grate structure.

6. In a mechanically clinkered gas generator, a foundation, a gas generating chamber having pipe connections for admitting air and steam, a rotating grate structure, and concentric annular surfaces resting in contact one upon another and forming a sliding gas-tight joint and supporting the grate structure, one of said surfaces being attached to the rotating grate structure and the other being provided in a fixed member resting on the foundation, and said surfaces constituting the sole means for supporting the grate on the foundation.
